(57) **CLAIM**

The ornamental design for an “electronic sphygmomanometer”, as shown and described.

DESCRIPTION

FIG. 1 is a front perspective view of an electronic sphygmomanometer;

FIG. 2 is a top perspective view thereof;

FIG. 3 is a rear perspective view thereof;

FIG. 4 is a front view thereof;

FIG. 5 is a rear view thereof;

FIG. 6 is a left view thereof;

FIG. 7 is a right view thereof;

FIG. 8 is a top view thereof; and,

FIG. 9 is a bottom view thereof.

The broken lines in the figures depict portions of the electronic sphygmomanometer that form no part of the claimed design.
